UNITED STATES PATENT OFFICE.

CHARLES W. WALTHEER, OF BROOKLYN, NEW YORK, ASSIGNOR TO WALTHEER & COMPANY, INC., OF NEW YORK, N. Y., A CORPORATION OF NEW YORK.

DESIGN FOR SAFETY PAPER.

Application filed July 13, 1926. Serial No. 18,349. Term of patent 14 years.

To all whom it may concern:

Be it known that I, CHARLES W. WALTHEER, a citizen of the United States, residing at Hotel Bossert, Hicks and Montague Streets, Brooklyn, in the county of Kings, city and State of New York, have invented a new, original, and ornamental Design for Safety Paper, of which the following is a specification, reference being had to the accompanying drawing, forming a part thereof.

The figure is a plan view of a portion of a sheet of safety paper showing my new design.

I claim:

The ornamental design for safety paper as herein shown and described.

In testimony whereof I affix my signature.

CHAS. W. WALTHEER.
